METHOD AND APPARATUS FOR LAUNCHING MARINE VESSEL

Ray Granville Parker, Staten Island, N. Y., assignor to Bethlehem Steel Company, a corporation of Pennsylvania

Application November 19, 1952, Serial No. 321,388

20 Claims. (Cl. 61—67)

This invention relates to a method of and means for launching marine vessels of the flat-bottom scow or barge type by moving them from an assembly line to a roller support from which they pivot and plunge into the water.

One object of this invention is to provide a means whereby a scow may be launched regardless of height or time of tide.

Another object of the invention is to provide for launching a scow from a production line without the use of derricks or other expensive cumbersome equipment and whereby the scow when it has been brought to proper position is self-launching.

Another object of the invention is to provide a means for launching a scow which requires a minimum amount of equipment which is quickly moved into position and which requires no renewal of parts for successive launchings.

Referring to the drawings:

Figure 1 is an elevation showing a scow with equipment ready for launching;

Figures 2a, b, c and d show the scow in four successive positions during launching;

Figure 3 is an elevation of the production line showing the various stages of assembling the scow;

Figure 4 is a plan view of the production line shown in Fig. 3;

Figures 5 and 6 show the roller support from which the scow drops into the water;

Figures 7 and 8 show the release trigger located at the rear of the inshore dolly trucks;

Figures 9 and 10 show the rollers and support on the inshore dolly trucks.

In recent years many of the major railroads have adopted a standard design for a deck scow. This standardized scow has a length of 90' 0", a width of 30' 0" with a depth of 9' 3" and is of the familiar double raked-end type. It has a light weight of 123 long tons. Such a scow of all welded construction is assembled on cribbing at four positions as shown in Figs. 3 and 4. For movement of the hulls from one position to the next on the production line, and thence to the launching support hydraulic-lift dolly trucks are employed. These are of a conventional design operating on standard railroad gauge tracks and with a floating platform supported by four hydraulic jacks. The hydraulic jacks have a lift of about 9 inches and are operated by an attached hand pump. Jacking of the platform is normally accomplished with all four jacks in intercommunication for a uniform load. Individual valves may be added, however, for individual or multiple jack control. The dollies have roller bearing wheels and, with a good track bed, roll with surprisingly little friction. Two tracks, one port and one starboard, are laid for each production line between the cribbing. The assemblies are lifted and shifted by using four dollies, two on each track. Unit No. 1 is lifted by placing the four dollies near the ends of the longitudinal bulkheads. In moving from both positions 2 and 3, the four dollies

2

are placed at the four intersections of the two longitudinal and the two midship transverse bulkheads. Propulsion for the moves is provided by a winch near the head of the ways hauling a single line through a sheave at the outboard end of the ways and thence to a bridle between the two outshore dollies.

The launching method, briefly, consists of rolling the scows off the end of the shipway.

The building height of the scow is determined by the height of the dolly truck platforms above the shipway and may be about 7 feet above the general yard level.

The height of the launching rollers above water level, however, is fixed by various factors including the dimensions of the scow. Since this height may be less than the building height of the scow, the problem becomes one of finding a method of lowering the scow on to the rollers and placing it such that it can pivot about the rollers and roll on into the water. Since the barge is being moved on four dolly trucks, a method of providing a hill for these trucks to roll down is used. Accordingly, a curved incline downward at the end of the tracks is provided that if the barge is propelled outboard the outshore pair of dollies go down the incline, lowering the outshore end of the barge until it comes in contact with the fixed rollers. Further travel down the incline completely transfers the outshore dollies' load to such rollers. Still further travel then starts the inshore dollies down the incline. The maximum outboard travel, however, is not sufficient to place the center of gravity beyond the rollers so that the vessel still will not pivot and roll freely from this extreme position. This necessitates the placing of rolls on the inshore pair of dolly trucks, with the required restraining and releasing rigging, so that the barge can roll on the two pairs of rollers until such time as it pivots and proceeds only on the outshore pair.

From position 4 or the final assembly position the scow 11 is in position for launching and is transferred to dolly trucks 12 and 13, mounted upon the tracks 14, to convey the scow 11 to roller support 15 at the end of the shipway 40 upon which roller support the scow pivots and drops until it is water-borne. The scow 11 rigged and ready for launching is shown in Fig. 1 and is shown to a smaller scale and without the rigging in Fig. 2 the four positions as follows: 2a the scow with the outshore dollies 13 part way down the incline at the end of track 14 and at this time the hull of the scow is just making contact with the rollers 15, 2b shows the scow all the way down the incline and ready for release. The outshore pair of dolly trucks 13 have transferred their load to the fixed roller support 15 and have rolled down the incline out of the way against positive stops at the bulkhead. The inshore pair of dollies 12 have gone down the incline practically to their limit such that the scow rests with the two fore and aft points of support under the two midship transverse bulkheads 16. The center of gravity of the scow is then approximately midway between the roller support 15 and the rollers on the inshore dolly 12. 2c shows the scow after release and when it has disengaged the dolly 12. At this point the center of gravity has just passed over the outboard rolls 15 and the scow has pivoted on them. 2d shows the scow as the inshore raked end is just passing over the roller support with the outshore end water-borne.

This scheme of launching requires many details not encountered in a conventional end launching. A means of propelling the scow along the tracks is required until such time as gravity takes over. At first glance, it appears that gravity would take over practically as soon as the outshore dollies 13 start down the inclined track 14. This is true but does not remain so. When the dolly load is transferred to the fixed roller support 15, the component in the direction of travel of the weight being borne

by the rollers is no longer sufficient to move the scow. This is due to the relatively flat angle of the hull in this position. Further travel down the ways increases this angle such that, at some point before the inshore dollies 12 are stopped, gravity will take charge and the scow would launch itself if released. To provide this propelling force, a weight 17 is suspended outshore from the roller support pile by a steel wire rope 18 through a single block, then over a sheave 19 on this support and thence back to and made fast to a girder 20 bolted to the inshore faces of the dollies 12. The pull from this line has to be at all times at least equal to the difference between the force of friction preventing rolling and the downward component of the barge.

A means of restraining the scow is required to prevent it from launching prematurely. If the scow were to start rolling before the inshore trucks were far enough down the way, its inshore end would roll off the inshore rollers before the center of gravity passed over the outshore rollers so that it would pivot inshore and drop inboard to the ground without launching. To provide this restraint, a large steel wire rope 21 is attached on the outshore end of the scow and thence under it to a releasing trigger 27 mounted on the girder 20 between the inshore pair of dollies 12. This is a single pendant attached to a bridle from the port and starboard bitts on deck. This restraining line is secured ashore through the releasing trigger 27 by a five part steel wire rope tackle as indicated in Figure 1. The fixed block of this tackle is secured at the head of the ways by a steel wire rope pendant 22 and the moving part 23 is led through a sheave to a winch at the head of the ways. This winch controls, by power lowering or hand brake, the lowering operation until the scow is released. To prevent the restraining line 21 from dropping and hanging loose under the scow after release, a manila preventor line 24 is secured to it and to the inshore end centerline cleat on deck. At the points of travel between those shown in Figures 2a and 2b, the propelling force is acting on the inshore dollies 12 and not directly on the scow. If, for any reason, friction should become excessive on the roller support at this time, it would be possible to pull the dollies down the ways without moving the scow, the dollies merely rolling under the hull. To prevent this from ever happening, the manila hauling lines 25 are installed, rigged from the inshore dollies around bitts on the deck. To prevent the outshore dollies 13 from freely rolling down the sharp incline of the track 14 and forcibly hitting the stops provided, manila connecting lines 26 are rigged between the outshore and inshore dollies. This permits the outshore dollies to contact their stops at the restrained velocity of the lowering operation.

The details of the launching operation are as follows: assuming the rigging as shown in Figure 1 is already completed. The scow is raised by the dollies about 3 inches. The upper two tiers of the outboard cribs (shown in Figure 3, position 4) are removed to provide necessary clearance for the travel down the incline. The winch operator starts the operation by lowering away against power. The propelling weight moves the scow down the incline until, first, it makes contact with the roller support, then the outshore dollies release their load and the scow continues until it reaches the releasing position. The winchman then stops the scow and secures the winch. Next, the manila hauling lines are removed, the trigger safety pins are pulled and the trigger is released. The scow then proceeds to launch itself as previously described and indicated by Figures 2b, c and d. The operation from the time the scow is lifted until it is waterborne takes possibly five minutes. The rigging is so designed that no one will be required aboard during the launching. A tug awaits the scow and puts a line aboard immediately it is waterborne to prevent it from drifting.

The outshore roller assembly 15 shown in detail in Figures 5 and 6. A series of four rollers 28 are mounted

in slides 29. A series of rollers rather than a single roller is desirable in order to reduce local pressure on the hull of the scow. These rollers pivot about a common center point 30 so that all rollers maintain contact with the hull at all times. For free sliding a brass shoe 31 is provided on the circumference of the track 32. The initial position of the slide prior to launching is at rest against an inboard stop, with the line of rollers inclined inshore about 5 degrees off the horizontal. The barge, therefore, first contacts the outshore rollers and rotates the set about the slide until all rollers are in contact. The series of four parallel rollers has the added advantage of providing a certain amount of directional stability to the hull when it rolls after pivoting. The rollers are 18 inches wide and are composed of 8 inch extra strong pipe with brass bearing bushings pressed into the ends. Instead of rollers it would be perfectly feasible to use a wooden saddle block of suitable form and which would be of suitable bearing area and could be well greased.

As a means of positively maintaining alignment and preventing any tendency of the hull to roll from a fore and aft line, vertical timbers 33 are secured to the bulkhead at the end of the shipway on each side of the production line. These uprights are placed with about 6 inches of clearance each side of the scows and are sufficiently high to cover the lower fender on the scow side. The timbers are greased and in the event the scow should move laterally, the side fenders would merely slide on the guides.

The inshore rollers 34, Figs. 9 and 10, mounted on the inshore dolly trucks 12 carry only half the maximum load of the roller assembly 15, hence two rollers in lieu of four per set are adequate. However, since the angle of the dolly truck relative to the bottom of the hull changes during the travel down the incline, as can be seen by Figures 2b and 2c, it is necessary that this set of rollers pivot through a few degrees to insure contact and equalize loadings on the two rollers. This is accomplished by mounting them both on a vertical plate 35, which in turn is merely restrained by the spaced vertical flat bars 37 but free to pivot at the round base 36, welded to plate 35, on the platform top. To insure equalized loading on the two pairs of rollers, a flexible hydraulic communication line is installed between the hydraulic systems of the two inshore dolly trucks.

Since there is fore and aft angular relative motion between the outshore dolly platforms and the bottom of the hull, transverse wood blocking, well rounded at the top, is used to support the scow under the transverse bulkhead for the launching operation.

A quick release trigger 27 (Figures 7 and 8) is necessary, also a means of attaching it to the inshore dollies 12 and of attaching a restraining line to this trigger. To accomplish this, a heavy steel girder 20 is bolted across the inshore face of these dollies. This girder assures movement together as desired of the two inshore dollies. For safety reasons workmen are not permitted under the scow at or after the time of release. To accomplish this, operation of the trigger is designed for remote control. The trigger is composed of two overlapping leaves as shown in Figure 8. A thimble spliced into the end of the releasing line 21 (shown as restraining line in Fig. 1) is hooked over the trigger finger 38. The intermediate leaf 39 merely changes the direction of motion. The cam on the upper end of this leaf bears against the plunger of an hydraulic jack 40. A flexible hydraulic line sufficiently long to extend out from under the hull is provided between the jack and a portable hand pump. A releasing valve on the pump permits the oil to drain back to the pump sump. A pendant safety pin 42 is provided to positively prevent any possible unhooking of the releasing line before release time. Safety pin 43 is provided to take the full load of the trigger in the event of any hydraulic failure to the system. In operation, the jack plunger is merely put into position and the releasing valve closed. Pressure automatically builds

up in the system as load comes on the trigger, applied by the releasing line. By this method there is never any force on the safety pins so they may be pulled with ease. The restraining tackle is secured to the trigger by means of links 44. The propelling line 18 is attached to a connection 45 on the under side of the girder. After pulling safety pins 42 and 43, the trigger is tripped by opening the releasing valve on the pump, which permits the two trigger leaves to rotate until their overlapping ends separate and thus release the releasing line 21.

All launchings in an extensive program have proven highly satisfactory, in all of these launchings the method shown and described has been used and no basic change of any sort has been necessary from the original design. The production line, as such, is not unique but the launching is believed to be quite different from anything previously tried for a vessel of this size. It is to be understood, however, that even though there is herewith shown and described a preferred embodiment of the invention the same is susceptible to certain changes fully comprehended by the spirit of the invention as herein described and the scope of the appended claims.

I claim:

1. A method of launching a marine vessel comprising advancing said vessel longitudinally from a production line to a roller support adjacent a body of water and sliding said scow forward until its center of gravity is beyond said support causing the vessel to pivot and plunge forward until it drops into the water.

2. A method of launching a marine vessel from a production line comprising successively moving said vessel from its cribbing to movable dolly trucks to a roller support about which it pivots forward and drops into the water when the vessel reaches a position where its center of gravity is on the outshore side of said roller support.

3. A method of launching a marine vessel comprising mounting the vessel on movable dolly trucks traveling upon tracks conveying the trucks with the vessel mounted thereon to a sliding support above a body of water, moving the vessel longitudinally forward on said sliding support to a position where the center of gravity of said vessel is on the outshore side of the support thus pivoting the vessel forward and causing it to plunge into the water.

4. A method of launching a marine vessel comprising mounting the vessel on inshore and outshore dolly trucks traveling upon tracks, conveying said vessel upon said trucks to a roller support above a body of water, continuing the forward motion of the vessel to transfer the load from the outshore dolly trucks to said roller support, and further continuing said forward movement until the center of gravity of the vessel has passed the support thus raising the vessel from the inshore dolly trucks and causing said vessel to launch itself by plunging forward into the water.

5. A method of launching a marine vessel comprising mounting the vessel on inshore and outshore movable dolly trucks traveling upon tracks, conveying said vessel upon said trucks to a roller support above a body of water, said tracks having a sharp downward incline adjacent the body of water to permit the load carried by the outshore dolly trucks to be transferred to the roller support, continuing the forward movement of the vessel to bring the vessel to a position where it will pivot about said roller support, lift from the inshore dolly trucks and plunge forward to drop into the water.

6. A method of launching a marine vessel comprising slidily supporting the inshore end of said vessel upon a pair of dolly trucks and non-slidily supporting the outshore end upon a second pair of dolly trucks, propelling said vessel forward upon said trucks by means of a tackle with suspended weight, transferring the load from the dolly trucks to a trunnion above a body of water but at a lower level than the dolly supports from which trunnion the vessel is self-launched by over-balancing.

7. A method of launching a marine vessel comprising providing a support for such vessel over a body of water, mounting the vessel on a pair of longitudinally spaced dollies inshore of said support, securing the vessel to the innermost dolly, moving the dollies forward until the forward end of the vessel overhangs said support, transferring the forward end of the vessel onto said support, releasing the vessel from the innermost dolly and propelling the vessel forward until its center of gravity lies beyond said support.

8. A method of launching a marine vessel comprising providing a support for such vessel over a body of water, mounting the vessel on a pair of longitudinally spaced dollies inshore of said support, securing the vessel to the innermost dolly, moving the dollies forward until the forward end of the vessel overhangs said support, transferring the forward end of the vessel onto said support by lowering the outermost dolly, releasing the vessel from the innermost dolly, and propelling the vessel forward until its center of gravity lies beyond said support.

9. A method of launching a marine vessel which comprises providing a support over a body of water, mounting the vessel upon a pair of dollies movable towards said support, securing the vessel to the rear dolly, moving said dollies and the vessel thereon towards said support until the forward end of said vessel overlies said support, continuing to move said dollies and the vessel thereon towards said support while simultaneously lowering the forward dolly until it becomes disengaged from said vessel and the forward end of the vessel rests upon said support, releasing the vessel from the rear dolly, and sliding the vessel over the rear dolly and the support until its center of gravity lies beyond the support.

10. Apparatus for launching a marine vessel comprising a support for such vessel located over a body of water, track means leading towards said support from a location inshore of said support, said track means descending towards said support at its outshore end, and pair of spaced dollies on said track means having vessel receiving upper surfaces located at a level above said support, means connecting said dollies, means for moving said dollies toward said support whereby the forward end of a vessel thereon may be brought to rest upon said support as said dollies move toward said support and the outer dolly traverses said descending track portion, means for releasably securing said vessel to said dollies and means for further moving such vessel towards said support upon the release of said securing means, until the center of gravity of such vessel lies beyond the support.

11. Apparatus for launching a marine vessel comprising a support for such vessel located above a body of water, a pair of longitudinally spaced dollies inshore of said support for receiving said vessel, means for securing said vessel to one of said dollies, means for moving said dollies toward said support while simultaneously lowering the outermost dolly to permit the forward end of the vessel to rest upon said support, means for disengaging the vessel from the dollies while moving said vessel forward until its center of gravity lies beyond said support.

12. Means for launching a marine vessel comprising inshore and outshore dolly trucks mounted upon tracks having a sharp incline outshore, propelling means for the inshore dolly trucks comprising a tackle with suspended weight, lines from the vessel to said inshore dolly trucks, dolly connecting line, a release trigger for said lines and a support adjacent the water.

13. Apparatus for launching a marine vessel comprising inshore and outshore dollies having upper surfaces for receiving a marine vessel, a track for said dollies having a downwardly inclined outshore end adjacent a body of water, a fulcrum support at the outshore end of said track above the level of the truck but below the level of said vessel receiving upper surfaces of said dollies, means connecting said dollies, means for releasably securing a vessel to said inshore dolly, means for propelling

said dollies towards said fulcrum support until the forward end of the vessel rests upon said support and the outshore dolly is out of contact with the vessel, and means for releasing said securing means to permit said vessel to slide forward and into the body of water.

14. Apparatus for launching a marine vessel comprising a body having an outer surface constituting a portion of a cylinder, a framework mounted on said body having a similarly curved surface adapted for sliding movement over said cylindrical surface and means on said framework for receiving a marine vessel.

15. Apparatus for launching a marine vessel comprising a body having an outer surface constituting a portion of a cylinder, a framework mounted on said body for sliding movement over said cylindrical surface, and a plurality of load receiving rollers mounted in said framework with their axes coplanar and extending parallel to the axis of said cylindrical surface.

16. A fulcrum for supporting a body comprising a pair of spaced frames, an upwardly curved track on each frame, a pair of supports each having similarly curved surfaces engaging said tracks and adapted for movement thereover, a frame carried by said supports, and a body supporting means mounted on said supports.

17. A fulcrum for supporting a body comprising a pair of spaced frames, an upwardly curved track on each frame, a pair of supports each having similarly curved surfaces engaging said tracks, a frame carried by said supports, and a body supporting means mounted on said supports, said body supporting means comprising a plurality of rollers.

18. A launching device for a marine vessel comprising

a framework located adjacent a body of water, a pair of laterally spaced tracks curving upwardly, outwardly and then downwardly in an arc of a circle from said framework and overhanging said body of water, a carriage mounted on said tracks for sliding engagement therewith throughout a path defined by said arcs and a plurality of rollers mounted on said carriage for receiving a marine vessel.

19. Means for supporting a body comprising a framework, a support pivotally mounted in said framework on a horizontal axis and extending above said framework, body receiving means mounted on said support and extending transversely on each side of said axis; arms secured to the upper end of said support and a pair of rollers mounted in said arms with their axes parallel to said first mentioned axis and on opposite sides of a plane extending vertically therethrough.

20. Means for releasably securing a load comprising a framework, a pair of levers pivotally mounted intermediate their ends on parallel axes in said framework with their inner ends overlapping, load receiving means at the outer end of the first of said levers, a member at the outer end of the second lever for resisting rotation of said lever as a result of a load upon the load receiving means of the first lever, and means for slowly withdrawing said member whereby said second lever may rotate until said overlapping ends separate and the load is released.
